[57] CLAIM

The ornamental design for a tire for vehicles, as shown and described.

DESCRIPTION

FIG. 1 is a perspective view of a tire for vehicles showing my new design, it being understood that the tread pattern is repeated throughout the circumference of the tire and that the opposite side is the same as that shown; FIG. 2 is a front elevation view thereof; and FIG. 3 is a side elevation view thereof.

FIG. 1

FIG. 2

FIG. 3
